COMBINED SAND AND WATER HEATER
Howard B. Fleming, South Portland, Maine, assignor to
Fleming Devices, Inc., South Portland, Maine, a corporation of Maine
Filed Sept. 8, 1965, Ser. No. 485,801
3 Claims. (Cl. 126—350)

ABSTRACT OF THE DISCLOSURE

A sand and water heater with a tubular chamber to be covered with sand, closed at its ends, and having an exhaust stack, a water tank having a loop conduit extending lengthwise of the chamber, and an oil burner of the gun type extending through one wall and having a thermostatic control, the thermostat being responsive to the water temperature.

The present invention relates to sand and water heater combinations adapted to eliminate from cement construction work, particularly at the start of a day's work, during freezing weather the necessity of thawing sand and providing water for use in cement mixing.

The general objective of the invention is to provide a combined sand and water heater that will be effective to ensure that a substantial supply of unfrozen sand and an adequate volume of water for use therewith in mixing cement is available at the job and ready for use even if left in the open and unattended overnight in freezing weather.

In accordance with the invention, the objective is attained with apparatus comprising a horizontal, tubular chamber to be covered with sand and having retaining walls closing its ends and dimensioned to extend above and laterally thereof. The chamber has an exhaust stack attached to and in communication with the interior of the chamber adjacent one wall. A water tank is provided with a loop conduit extending through the other wall a substantial distance lengthwise of the upper part of the interior of the chamber. A heater for the chamber is supported by said other wall and has a circuit provided with a thermostat connected to the tank to be responsive to the temperature of the water contained therein.

In the accompanying drawings, there is shown an illustrative embodiment of the invention from which these and other of its objectives, together with its novel features and advantages, will be readily apparent.

In the drawings:

FIGURE 1 is a side view of the apparatus showing the chamber as longitudinally and vertically sectioned,

FIGURE 2 is a section, on a reduced scale, taken approximately along the indicated lines 2—2 of FIGURE 1, and

FIGURE 3 is a section taken approximately along the indicated lines 3—3 of FIGURE 1.

The heater illustrated by the drawings consists of a cylindrical chamber 10 of substantial length, conveniently a length of corrugated pipe, closed at its ends by walls 11 and 12 welded thereto. Each wall extends laterally of and above and below the chamber 10 so as to provide supports positioning the chamber 10 horizontally and providing retainers for sand, generally indicated at S, deposited between them and covering the chamber 10. The chamber

2

10 has a centrally located eye 13 and is also provided with member 14, each welded to a wall and to the chamber 10 to provide eyes, the several eyes being used in hoisting the heater into and out of positions of use at the job. The chamber 10 also has, adjacent its wall 11, a stack 15 in communication with the interior thereof and extending vertically above the walls 11 and 12 so as to be exposed when the heater is covered with sand.

The wall 12 has a port opening into the chamber 10 closed by a plate 16 having a port 16a controlled by a hinged damper 16b. A flanged sleeve 17 to which is bolted a flanged sleeve 18 opens into the chamber 10. The barrel 19 of a generally indicated oil burner unit 20 extends through the sleeves and into the chamber 10 to the desired extent. The oil supply for the oil burner unit 20 is not shown but it may be attached to the heater or it may be an existing source of supply or a portable tank.

Supporting arms 21 and 22 are secured to the wall 12 and these arms support a water barrel 23 having a generally indicated loop 24 extending through the wall 12 and into the chamber 10 with its closed end 24a adjacent the stack 15. The upper arm 24b is supported approximately horizontally in the chamber 19 by hangers 10a and is in communication with the interior of the barrel 23 centrally thereof while the lower arm 24c is downwardly inclined and is in communication with the interior of the barrel close to the bottom thereof. An adjustable thermostat 25 is connected in a loop 26 to be responsive to the temperature of the water in the barrel 23 and controls the operating circuit 27 of the oil burner unit.

It will be apparent, from the foregoing, that when the chamber 10 is covered with sand and the water barrel 23 is full of water, the burner unit is operated whenever the temperature of the water therein drops to a predetermined minimum thereby to prevent its freezing. The same operation ensures that the sand will be so heated that it may be used whenever needed in mixing a supply of cement.

I claim:

1. A combined sand and water heater comprising a horizontal, tubular chamber to be covered with the sand to be heated and kept warm, a wall closing each end of said chamber, at least one wall extending above and laterally of the chamber to constitute a sand retaining wall, an exhaust stack in communication with the interior of said chamber remote from said one wall, a water tank having a loop conduit extending through said wall a substantial distance lengthwise of the upper part of the interior of said chamber, and an oil burner of the gun type with its barrel extending into said chamber through said one wall and having a control circuit provided with a thermostat, said thermostat being connected to said water tank to be responsive to the temperature of the water therein whereby the rate of sand heating is determined by the rate at which the water cools.
2. The sand heater of claim 1 in which the sand retaining wall has a sleeve opening into the chamber and the barrel of the oil burner extends through and is supported by the sleeve thereby to support the oil burner.
3. The sand heater of claim 1 and a support secured to the sand retaining wall adjacent the bottom thereof and one side thereof, and the water tank is mounted on the support.
